[57] CLAIM

The ornamental design for a combined packaging container and toy construction block, as shown.

DESCRIPTION

FIG. 1 is a front elevational view of a combined packaging container and toy construction block showing my new design;

FIG. 2 is an elevational view looking from the right of FIG. 1;

FIG. 3 is a top plan view;

FIG. 4 is a bottom plan view; and

FIG. 5 is a longitudinal sectional view thereof taken along the line V—V in FIG. 3.
